(57) **CLAIM**

The ornamental design for a ceiling lamp, as shown and described.

DESCRIPTION

FIG. 1 is a front perspective view of a ceiling lamp, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

In the drawings, the broken lines depict portions of the LED round high bay that form no part of the claim. Furthermore, the portions of the view in FIG. 7, shown by a lower tonal value and bordered by broken lines, form no part of the claim.

1 Claim, 8 Drawing Sheets
